SUPERCHARGER

Charles Raymond Waseige, Rueil, France

Original application March 18, 1936, Serial No. 69,497. Divided and this application May 19, 1938, Serial No. 208,752. Renewed February 26, 1940. In Japan August 1, 1935

3 Claims. (Cl. 230—114)

My invention relates to aircraft power plants including at least one engine provided with its own rotary supercharger. One object of my invention is to devise air feeding means to each 5 supercharger so as to increase the efficiency ratio of the supercharger. Another object is to supply a flow of air into the central region of the rotary impeller with a minimum loss of pressure. A further object is to cause the air stream 10 on its way to the impeller to rotate at a high speed and substantially coaxially with and in the same direction as the impeller when about to enter the latter.

With these and other objects in view my invention resides in the novel arrangement of parts hereinafter described and more fully pointed out in the claims.

This application is a division of my copending application #69,497 filed March 18, 1936, now Patent #2,120,821 of June 14, 1938.

An embodiment of my invention is diagrammatically illustrated in longitudinal section in the annexed drawing.

1 denotes the crankcase of an engine the front 25 face of which carries the casing of a centrifugal supercharger or compressor 2 having its discharge side connected to the engine cylinders 3 by delivery pipes 4. The compressor is enclosed within a stream lined shell 5 coaxial with the 30 compressor and having a central orifice 6 connected to the central intake 7 in the supercharging casing by a rectilinear duct 8. Inside said duct is stationarily fitted a screw deflector 9 the pitch of which gradually decreases from the 35 inlet orifice 6 to its end centrally projecting into the compressor casing. The duct 8 flares somewhat outwardly from the intake 7 of the compressor to the inlet orifice 6 and the shell 5 extends from the engine crankcase edge to the 40 foremost end of the duct 8.

It will be readily understood that when a stream of air is flowing through the duct 8 to

the supercharger 2 it has progressively imparted thereto a rotary motion by the screw deflector 9 and will rotate at high speed about the supercharger axis when about to enter the impeller. The pitch of the deflector 9 and the direction 5 of rotation of the impeller are chosen in order that the air will rotate in the same direction as the impeller.

In this arrangement the loss of pressure is reduced to a minimum owing to the rectilinear 10 formation of the duct 8.

What I claim is:

1. A supercharger for engines, comprising a centrifugal compressor having a centrally disposed rectilinear air duct of truncated form extending laterally therefrom, said air duct being longitudinally tapered toward the compressor, and a stationary helical deflector disposed within said air duct, the pitch of said deflector decreasing progressively toward the compressor. 15

2. A supercharger for engines, comprising a centrifugal compressor having a centrally disposed rectilinear air duct of truncated form extending laterally therefrom, said air duct being longitudinally tapered toward the compressor, a 25 stationary helical deflector disposed within said air duct, the pitch of said deflector decreasing progressively toward the compressor, and a stream-lined shell forming an air-tight enclosure for said compressor and air duct and having a centrally disposed opening in register with the intake end of said duct.

3. A supercharger for engines, comprising a centrifugal compressor having a centrally disposed rectilinear air duct of truncated form extending laterally therefrom, said air duct being longitudinally tapered toward the compressor, and a fixed, truncated screw disposed within said air duct, the pitch of said screw decreasing progressively towards the compressor. 35

CHARLES RAYMOND WASEIGE.
